RIBBON LOOM

Marguerite G. Brooks, Darien, Conn.

Application October 2, 1952, Serial No. 312,726

6 Claims. (Cl. 87—31)

1

This invention relates to a ribbon loom, and has for an object to provide a suitable construction of the device designed for effectively weaving many kinds of braids, trimmings and bobbin laces, and similar narrow woven fabrics.

Another object is to provide a construction which may be packaged and shipped in a flat, knock-down condition and then easily assembled for the weaving operations.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a top plan view of the device showing it assembled and in use;

Fig. 2 is a top plan view of a portion with the spread removed to show how the parts are put together;

Fig. 3 is a section substantially on line 3—3 of Fig. 2;

Fig. 4 is an enlarged section substantially on line 4—4 of Fig. 1;

Fig. 5 is a plan view of a portion of the spread foundation in flat condition;

Fig. 6 is a plan view of the box in a flat condition;

Fig. 7 is a side view of one of the discs at the ends of the bolster, and

Fig. 8 is a side view of one of the cradles for supporting the bolster.

This ribbon loom is designed to be used with a series of spindles or bobbins on which threads are wound, to make bobbin lace, braids, or similar narrow fabrics. It comprises a central bolster 10 of substantially cylindrical shape mounted to turn or rotate about a horizontal axis by means of a suitable support, with an inclined playground or field surrounding the bolster, or at least at the front thereof, for supporting the bobbins carrying the thread, and to keep these bobbins or spindles in order while in use and also to maintain the proper tension on the threads. The bolster may be of different constructions, but it preferably comprises a central wooden dowel or pin 11 forming a supporting shaft for the bolster, and wrapped around the shaft is a body of layers of cloth, felt or other suitable fabric 12, which may be formed by either tacking or gluing one end of a strip of this material to the member 11 and then rolling it on this material along a flat sur-

2

face to build up the proper size, preferably about three or four inches in diameter, or twelve inches in circumference, and of a length of about five inches, and then this is covered with a covering layer 13 of any desired color of a felt material, this bolster being designed to hold the pattern pins 14 to permit them to be stuck into this material at the proper location and spacing for weaving the threads about them to produce a desired pattern.

The bolster is supported in a suitable support, in the present case comprising an open topped box 15. This is preferably of cardboard comprising a bottom wall 16, end walls 17 and side walls 18. It is cut to substantially the shape shown in Fig. 6 when in flat condition, and scored at lines 19 so that the ends 17 and sides 18 and 18a can be folded up to form the open topped box. Extending upright in the opposite ends of the box are two cradles 20 longitudinally curved at the top 21 and provided with a recess 22 in which the end of the pin or shaft 11 is seated, these cradles being of sufficient height to support the bolster above the bottom of the box for proper clearance to permit free rotation of the bolster. There is also preferably a disc of cardboard or other suitable material 23 placed over the ends of the bolster and between these ends and the cradles to hold the fabric material to shape and to prevent its rubbing on the cradles 20.

About the bolster is placed a spread foundation 24 of cardboard or other suitable material, and this is preferably circular, as shown in Figs. 1 and 2, and is inclined downwardly and outwardly from the upper part of the box and the bolster, at least at the front side 25 of the bolster. Fig. 5 shows the greater portion of it in the flat condition, and it is cut with a central substantially rectangular opening 26 and with free edges spread at one side as at 27, so that when placed together in a circle about the box with this box located in the opening 26 these two edges will come together and the field or spread foundation will be inclined downwardly and outwardly from the upper part of the box and bolster, as shown in Figs. 3 and 4. On top of this spread foundation is placed a spread 28. This spread is preferably of any suitable cloth or padded plastic material cut to lie on the inclined spread foundation 24 to cover the top surface of this foundation, as shown in Fig. 1, to give a finished appearance and to support the spindles or bobbins 29 carrying the threads 30 for weaving the lace or narrow strip material about the pins 14.

In assembling the device the flat piece shown

in Fig. 6, of cardboard or similar material, is laid on a support and the sides 17 and 18 bent to an upright position to form the sides of an open topped box. They may be held in this position while assembling with the other parts by placing a small elastic band around the side members below the openings formed adjacent the free edges of these sides for the purpose of securing the sides of the box together in the upright position, and also to secure the spread foundation 24 to this box. This foundation adjacent the opposite side 26a of the opening 26 from the free edges 27 and adjacent the opposite ends of this side is provided with a pair of holes 31. One side member 18 of the box is provided with a pair of similar holes 32 adjacent the opposite corners. The end walls 17 adjacent these corners are provided with holes 33 and in the foundation on the opposite sides of the corners from the holes 31 are provided holes 34. At the opposite corners of the side edge 26b this foundation is provided with holes 35, and at the opposite sides of the adjacent corners with holes 38. The opposite corners of the end walls 17 of the box are provided with holes 36 and the opposite side wall 18a is provided adjacent its corners with openings 37, and adjacent its center with a pair of holes 40. The foundation 24 adjacent each free edge 27 is provided with a row of holes 39, 41, 42, 43 and 44.

After the sides of the box have been bent to the upright position, this foundation 24 is placed around the box with the box in its central opening 26, and with the free edges 27 together. This causes the walls of the spread foundation 24 to incline downwardly and outwardly from the upper part of the box and the bolster after it is mounted in the box. To secure the spread foundation to the box a thread or cord lacing 45 is used. As the first step, the opposite ends of this lacing are laced upwardly through the two holes 31 in the foundation 24 from its lower or under side, leaving the center part of the lacing on the under side of this foundation, as shown in dotted lines, Fig. 2. Then, beginning with the end at the left side and proceeding along the left, this end is threaded through the holes 32 and 33 at the adjacent corner of the box, then down through the adjacent hole 34 in the foundation across to the opposite hole 34 on the under side of the foundation, as shown in dotted lines, up through the hole 34 and through the two holes 36 and 37 in the adjacent corner of the box, down through the hole 38 in the foundation, up through the hole 39, and through the adjacent hole 40 in the box. The same is done with the right hand half of the lacing at the other end of the box, and the threads are crossed at 45a. Then the two sides of the lacing are laced down through the rows of holes 39 to 44 on the opposite sides of the free edges 27 alternately crossing over from one side to the other, as shown in Fig. 2, to secure the two ends 27 of the foundation together, and then the free ends 45b of the lacing may be tied in a bow knot.

After the box and the foundation 24 are thus secured together the two cradles 20 may be inserted in an upright position at the opposite ends of the box at the inner sides of the end walls, and the bolster may be placed in position as shown in Figs. 1 and 4. Then the spread 28 may be placed about the box to lie on the top of the spread foundation 24, and its opposite ends secured together about the box by tape or ribbon 46, secured around the edge of the central opening in this spread, as shown in Fig. 1. The edges of this spread may be bound by a suitable tape or ribbon

47. The rear side wall 18a of the box may also be provided with a hole 48 through which may be passed a bolster tape 49 which may be pinned to the bolster at 50 to prevent the bolster turning under tension of the threads from the bobbin during the weaving operation.

It will be seen from the above that the device may be shipped and sold in the flat or knock-down condition and then readily assembled for the weaving operation. Different bolsters can be readily made and used for different designs, leaving unfinished strips on one bolster while shifting to another if desired, it being merely necessary to lift one from the box and replace it with another. The downwardly and outwardly inclined spread foundation and spread, particularly at the front of the bolster, support the bobbins in order, as shown in Fig. 1, so that any particular bobbin when wanted may be readily located and picked up for the weaving operation, and also the downwardly and outwardly inclined arrangement of the supporting surface for these bobbins, particularly at the front of the bolster, maintains a proper and uniform tension on the threads about the pattern pins 14, as the bobbins tend to slide down the inclined surface.

A strip 51 with the desired design drawn on it and locations for the pins 14 indicated may be fastened on the bolster. The spread foundation and spread for the size bolster noted above is preferably about eighteen inches in diameter.

Having thus set forth the nature of my invention, I claim:

1. A ribbon loom of the character described comprising an open topped box member having upright end and side walls, a substantially cylindrical bolster mounted in the box to turn about a substantially horizontal axis and provided with a surface to receive pattern pins, and a supporting field for bobbins extending about the box including a portion at the front of the bolster inclined downwardly and forwardly therefrom to support the bobbins and maintain a tension on the threads extending from the bobbins to pins in the bolster.

2. A ribbon loom of the character described comprising a support, a substantially cylindrical bolster mounted in the support to turn about a substantially horizontal axis and provided with a surface to receive pattern pins, and a supporting field for bobbins extending longitudinally of the bolster at the front thereof and inclined downwardly and forwardly therefrom to support the bobbins and maintain a tension on the threads extending from these bobbins to pins in the bolster.

3. A ribbon loom of the character described comprising an open topped box member having upright end and side walls, a substantially cylindrical bolster mounted in the box to turn about a substantially horizontal axis and provided with a surface to receive pattern pins, a supporting field for bobbins extending about the box comprising a foundation member of sheet material provided with an opening in which the box is located, the side and end walls of the box and the foundation being provided with lacing holes adjacent the corners of the box, and a lacing passing through said holes and securing the box and foundation member together with said member inclined downwardly and forwardly away from the bolster.

4. A ribbon loom of the character described comprising an open topped box member having upright end and side walls, a substantially cylind-

drical bolster mounted in the box to turn about a substantially horizontal axis and provided with a surface to receive pattern pins, the mounting for the bolster comprising upright cradles at the inner sides of the end walls of the box each provided with a recess in its top edge, the bolster including an axial shaft including projecting ends seated in said recesses, and a supporting field for bobbins extending about the box including a portion at the front of the bolster inclined downwardly and forwardly therefrom to support the bobbins and maintain a tension on the threads extending from the bobbins to pins in the bolster.

5. A ribbon loom of the character described comprising an open topped box member having upright end and side walls, a substantially cylindrical bolster mounted in the box to turn about a substantially horizontal axis and provided with a surface to receive pattern pins, a supporting field for bobbins extending about the box comprising a foundation member of sheet material provided with a rectangular opening in which the box is located and opening outwardly from one side of the box with abutting free edges, 25 the side and end walls of the box and the foundation being provided with lacing holes adjacent the corners of the box, the foundation being also provided with a row of lacing holes adjacent each of said free edges, and a lacing passing through said holes and securing the box and

10

15

30

foundation member together with said member inclined downwardly and forwardly away from the bolster, and also securing the abutting free edges together.

6. A ribbon loom of the character described comprising an open topped box member having upright end and side walls, a substantially cylindrical bolster mounted in the box to turn about a substantially horizontal axis and provided with a surface to receive pattern pins, a supporting field for bobbins extending about the box comprising a foundation member of sheet material provided with a rectangular opening in which the box is located, a lacing passing through the upright walls of the box and the foundation member securing them together with said member inclined downwardly and forwardly from the bolster, and a spread of flexible covering material on and covering the top surface of the foundation member around the box and forming a supporting surface for the bobbins.
